(57) **CLAIM**

The ornamental design for a vehicle control console, as shown and described.

DESCRIPTION

FIG. 1 is a front view of the vehicle control console showing my new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a perspective view thereof.

FIG. 8 is a enlarged view of part I of FIG. 3 thereof; and, FIG. 9 is a enlarged view of part II of FIG. 4 thereof.

The broken lines showing of the environment are for illustrative purpose only and form no part of the claimed design.
